UNITED STATES PATENT OFFICE.

WILLIAM BLACKMORE, OF SHARON, PENNSYLVANIA, ASSIGNOR TO NATIONAL MALLEABLE AND STEEL CASTINGS COMPANY, OF CLEVELAND, OHIO, A CORPORATION OF OHIO.

SHOCK-ABSORBING MECHANISM.

Application filed January 6, 1926. Serial No. 79,602.

Fig. 1 is a plan, partly in section, of a shock absorbing mechanism embodying my invention; Fig. 2 is an end elevation thereof with the wedge follower removed; Fig. 3 is an elevation of the inner face of the wedge follower; Fig. 4 is a side elevation, partly in section, of the follower wedge; Fig. 5 is a side elevation of one of the shoes; and Fig. 6 is a rear elevation thereof.

10 My invention relates to shock absorbing mechanism, and particularly to friction draft gears for railway vehicles of the type described in Letters Patent No. 1,192,571 of Ernest H. Schmidt, granted July 26, 1916, and No. 1,301,809 of Chester K. Brooks and Ernest H. Schmidt, granted April 29, 1919. My invention comprises an effective releasing mechanism and various features which I shall hereinafter describe and claim.

20 Referring to the drawings, the central friction member 2 has longitudinally extending, outwardly radiating arms 3 and terminates at its rear end in an enlarged base 4. Friction shoes 5 seat upon the friction faces 25 of the outwardly radiating arms 3. Each friction shoe 5 has a wedging surface 6 engaged by a wedging surface 7 on the wedge follower 8, a rearwardly extending dowel 9 and a spring seating surface 10 about the 30 dowel, preferably engaged by the inner coil 11 of a spring element which at its rear end bears against the base 4. The outer coil 12 of the spring element likewise bears at its rear end upon the base 4, but at its 35 forward end engages a surface 13 on the wedge follower 8. The rear face of the shoe 5 is recessed at 14 to keep the outer spring coil 12 normally out of engagement with the shoe 5.

40 In the operation of my improved gear, as compression abates the heavy coil 12 will force the wedge 8 outwardly, thus breaking the adhesion of the wedge 8 to the shoe 5, and leaving the inner spring coil 11 free to move the shoe 5 outwardly and release it 45 from its frictional engagement with the central friction member. If, however, the spring 11 is not powerful enough to break the adhesion of the shoe to the central friction member, as soon as the wedge 8 has moved a distance equal to the clearance space 50 between the face 14 and the end of the spring 12, the spring 12 will come into engagement with the face 14, and thus the full force of 55 both springs 11 and 12 will be brought to bear

upon the shoe 5, and will ensure its release. The shoe and wedge may be equipped with overlapping hooks 15 on the wedge and corresponding shoulders 16 on the shoe. These hooks and shoulders normally have a small 60 clearance space therebetween, but in case the shoe sticks to the central member 2, the movement of the wedge under impulse of the spring 12 will cause the hooks 15 to engage the shoulders 16 and pull the shoe free from 65 the central member.

I have found that gears constructed in accordance with my invention are particularly effective in service and that an extremely satisfactory release after compression is obtained. It is also to be observed that, while the compression spring 11 is of less capacity 70 than those heretofore used in gears of the type described, the frictional capacity of the gear is not substantially diminished.

75 While I have described my invention as applying to both sides of the gear, it is obvious that, if desired, it may only be applied to one shoe and its accompanying mechanism, while the other shoe or shoes may be so arranged that the entire reaction of the accompanying spring mechanism is directed against such other shoe or shoes and not divided between shoe and wedge. In such case the spring seat 13 would be removed 80 from the side of the follower wedge opposite such other shoe or shoes.

85 The terms and expressions which I have employed are used as terms of description and not of limitation, and I have no intention, in the use of such terms and expressions, of excluding any mechanical equivalents of the features shown and described, or portions thereof, but recognize that various structural modifications are possible 90 within the scope of the invention claimed.

95 What I claim is:

1. In a frictional shock absorbing mechanism, a longitudinally-extending included friction member having a plurality of diverging longitudinally extending friction faces; a friction shoe seating against each of said faces; a wedge follower engaging said shoe; and a plurality of springs, one of which is capable of successively transmitting 100 pressure to the wedge and a shoe as compression abates, and the other of which transmits pressure to the shoe and during compression causes the frictional engagement of the shoe on the central member and also the 105 110

release of the shoe from such engagement after the wedge has been released by the first mentioned spring.

2. In a frictional shock absorbing mechanism, a longitudinally-extending included friction member having diverging arms extending longitudinally; friction shoes seating upon said arms; a wedge follower engaging said shoes; and a plurality of coil springs nested in each other, one coil normally transmitting pressure to a shoe, and another coil normally engaging said wedge, the second mentioned coil being adapted to transmit pressure to the shoe and assist in breaking its adhesion to the central member after forcing the wedge outwardly.

3. In a frictional shock absorbing mechanism, a longitudinally-extending included friction member having a plurality of diverging longitudinally extending friction faces; a friction shoe seating against each of said faces; a wedge follower engaging

said shoes; and a plurality of springs, one of which transmits pressure to the wedge and another to a shoe, the shoe lying in the path of movement of the first mentioned spring but normally out of engagement therewith, said spring, however, being adapted to transmit pressure to said shoe after it has moved said wedge to released position.

4. In a frictional shock absorbing mechanism, a longitudinally-extending included friction member having diverging arms extending longitudinally; friction shoes seating upon said arms; a wedge follower engaging said shoes; and a plurality of coil springs nested in each other, one coil normally transmitting pressure to a shoe, and another coil normally engaging said wedge, the second mentioned coil being of substantially higher capacity than the first mentioned coil and being arranged to ensure release of the wedge from the shoe.

WILLIAM BLACKMORE.
